PROOF PRESS

Freeman Barney, Spring Lake, Mich., assignor to
 The Challenge Machinery Company, Grand
 Haven, Mich., a corporation of Michigan

Application July 26, 1948, Serial No. 40,651

3 Claims. (Cl. 101—269)

1

This invention is directed to a novel and better proof press, which is used in the art of printing for printing proof sheets which, after a sheet has been printed, may be examined and any necessary corrections made in the type form before the form is transferred to the regular printing press for reproduction in large numbers. Such proof presses are used to print on a sheet of paper, and are manually operated to move a cylinder around which the paper is carried relative to the type form and imprint upon the paper the type and other characters which are fixed in a form on the bed of the press.

The present invention has among its objects and purposes the provision of novel structure for attaining the best operating condition of the mechanism to grip the paper at one end edge and secure it at such end edge to the rotatable cylinder while the cylinder is stationary, and furthermore automatically gripping said end edge of the paper by rotation of the handle by which the cylinder is manually turned in one direction, such grip of the paper being released at any position of the cylinder with reference to the other parts of the machine by a reverse turning movement of the handle. It is a further object and purpose to provide a machine of the type described wherein the cylinder is never disturbed with reference to any impression position which it may occupy. The gears on the cylinder and racks with which said gears engage are always in full mesh and there is no relative upward or downward movement of said cylinder gears with respect to the racks with which they engage, but instead the carriage carrying the cylinder and the racks with which the cylinder engages may be moved upwardly a short distance with reference to the printing form below the cylinder or lowered to printing position, thereby obtaining a greater accuracy in printing and insuring that the cylinder will not be disturbed or changed from impression position when it is again lowered after being raised. Novel structure for attaining these objects and purposes, and many others which will appear, may be understood from the following description, taken in connection with the accompanying drawings, in which,

Fig. 1 is a side elevation of a proof press constructed in accordance with my invention,

Fig. 2 is a vertical section transversely of the cylinder and the grip mechanism associated therewith, substantially on the plane of line 2—2 of Fig. 1,

Fig. 3 is a fragmentary, somewhat enlarged

2

vertical section, substantially on the plane of line 3—3 of Fig. 2, illustrating a detail of the mechanism,

Figs. 4 and 5 are fragmentary enlarged elevations, illustrating the mechanism used for elevating and lowering the cylinder and its carriage and the tracks on which the carriage moves, Fig. 4 showing the position when lifted and Fig. 5 when lowered to printing position,

10 Fig. 6 is a vertical section transversely of the printing cylinder, substantially on the plane of line 6—6 of Fig. 2,

Fig. 7 is a fragmentary end elevation showing the vertical retaining and guiding means at the ends of the carriage tracks,

Figs. 8 and 9 are enlarged transverse sections, substantially on the planes of lines 8—8 and 9—9 of Fig. 10, and

Fig. 10 is a side elevation of one of the cylinder carriage tracks of the machine.

Like reference characters refer to like parts in the different figures of the drawings, and the sectional views are taken looking in the directions indicated by the arrows.

15 In the construction of the proof press as disclosed, a frame is provided, having four vertical corner posts 1 at the corners of the frame. At the sides of the frame midway between the corner posts are intermediate vertical posts 2. Horizontal longitudinal bars 3 spaced from each other connect the posts, and the posts at opposite sides of the frame may also be connected by cross members if desired. At the upper ends of the posts are beams 4 extending horizontally from one side to the other of the machine and between the beams a horizontal type bed 5 extends lengthwise of the machine, strengthened and reinforced at its sides by side rails 6 (Fig. 2). The bed, beams and frame are fixed against movement. On the upper side of the bed 5 the form, including the type and other imprinting characters, is located, as indicated at 7, in Fig. 2.

20 At opposite sides of the side rails 6 of the bed 5 two elongated horizontal track members 8 are located. They are connected with the side rails 6 of the bed (Figs. 8, 9 and 10) so as to be held from longitudinal movement with respect thereto, but with connections which permit a limited vertical movement of the tracks 8. At the outer sides of the side rails 6 rectangular, somewhat elongated recesses 9 (Fig. 8) are provided, one adjacent each end of the rails 6, in which a block 10 is located, the vertical dimension of which is slightly less than the vertical dimension of the recess 9. The blocks 10 are

connected to the rails 8 by screws 11. Also screws 12 pass through the tracks 8 and thread into the rails 6 of the bed, the heads of the screws being in recesses 13 cut in the outer sides of said track members 8, and the passages through the tracks 8 for the shanks of the screws 12 are short vertical slots 14. Therefore, the rails 8 may have a limited vertical movement from a lower to an upper position, and vice versa. At each end of the bed and at each side thereof a vertical plate 15 is secured which overlaps the adjacent end of the track 8. This provides vertical guides for the ends of the tracks 8 in any upward or downward movement thereof and holds them against longitudinal movement with respect to the type carrying bed.

At the outer side of each of the corner posts 1 and at their upper ends and extending thereabove, a cylinder 16 with a closed bottom is secured, which houses a strong coiled compression spring 17. The upper ends of the springs 17 bear against the under edges of the tracks 8 and serve to lift the weight thereof and of the cylinder and its carriage which are mounted to traverse the tracks. One of these springs 17 is located near each end of each of the track bars 8. A bracket 18 is secured to and extends downwardly from each track 8 adjacent each of the spring carrying cylinders 16. Shafts 19, one at each end of the machine, extend between the end brackets 18 carried by the track bars 8 and are mounted for rocking movement therein. On each of the shafts near each end thereof an eccentric 20 is secured or formed integral with the shaft which is located directly underneath a horizontal bearing surface 21 made at the upper side of a recess in the lower portion of the associated beam 4. A rocking of the shaft 19 to the position shown in Fig. 4 from that shown in Fig. 5, changes the position of the tracks 8 which are vertically moved limited distances upward or downward by rocking the shafts 19, dependent upon the direction of rocking movement given to the shafts. When the cams are in the position of Fig. 4 with their full portions against the surfaces 21 the tracks 8 are pulled downward against the action of the springs 17 and the carriage and cylinder are pulled downward so that by action of the rollers 32 the paper is pressed firmly against the type on the bed. When the cams are moved to the position of Fig. 5 they release the tracks so that they, together with the carriage and cylinder, are lifted by the springs 17 raising the cylinder to release the paper for removal.

From the shafts 19 arms 22 extend radially, to the outer end of each of which a vertical bar 23 is pivotally connected at its upper end and extends downwardly nearly to the floor (Fig. 1). Said bars 23, one adjacent each end of the machine, are pivotally connected at their lower ends to levers or arms 24 mounted on transverse shafts 25 carried in journals at the inner sides of and near the lower ends of the posts 1. Generally horizontal links 26 are pivotally connected at one end to the other arms on shafts 25 and extends toward each other to substantially the middle of the machine, where they are connected at their inner ends to the opposite ends of a bar 27 which is secured to a horizontal rock shaft 28, extending between posts 2, to which the bar 27 is secured midway between its ends. The shaft 28 at an outer end thereof is provided with a foot lever 29, said lever having connection at its middle to the shaft 28 and extending in opposite directions therefrom. Engaging the ele-

vated end of the foot lever with the foot rocks the shafts 19 simultaneously in one direction, and then by depressing the other end of the lever 28 which has been elevated, the rocking of the shafts 19 simultaneously in opposite directions occurs, so that the longitudinal tracks 8 are simultaneously and equally raised or lowered.

At the outer upper corners of the track members 8, lengthwise thereof, a groove is cut in which a rack 30 is located and secured, leaving inner upwardly projecting track sections or ribs 8a which extend the length of the track members. A carriage is mounted to move back and forth on the track members 8 having two spaced vertical sides 31, one at the outer side of each of the tracks 8, and with under rollers 32 spaced from each other on shafts 33 extending between the carriage sides 31, the rollers 32 bearing against the under longitudinal edges of the tracks 8. Upper rollers 34 ride upon the projecting ribs 8a of the tracks 8 and shafts, upon which the rollers 34 are mounted, may extend between the sides 31 of the carriage. Thus the carriage and the cylinder hereafter to be described, mounted thereon, may be moved back and forth over the tracks 8, as is evident.

A hollow cylinder 35 having vertical ends 36 and with a segment of the cylinder wall removed at one side, slightly less than 90° in extent, as indicated at 37, has a gear 38 secured at the outer side of each of the ends 36. The two gears 38 mesh with the racks 30. A sleeve 39 extends axially of the cylinder and to which the cylinder ends are attached and is mounted in bearings 40 at its ends in the vertical sides 31 of the carriage. A rod 40 extends through the length of the sleeve and beyond one end of it, beyond one side of the carriage. A crank handle 41 is secured to the projecting end of the rod. At the end of the sleeve adjacent the crank (Fig. 3) recesses 42, diametrically opposed to each other, are cut or otherwise produced. A pin 43 extends through the rod 40 and beyond it at opposed sides, the ends of the pins being located in the recesses 42. Thus on turning the rod 40 by means of the crank 41 in a counter-clockwise direction (Fig. 3), before the sleeve 39 and the cylinder secured thereto start to turn, the projecting end portions of the pins 43 must traverse the slots 42. On reversal of turning movement of the rod 40 the end portions of the pin 43 again traverse the slots 42 in the reverse direction before the cylinder will turn to accompany the turning of said rod.

A tympan 44 is secured at one end to a bar 45 extending lengthwise of the cylinder 36 adjacent one side of the opening 37 and covers the outer surface of the cylinder to the opposite side of the opening. A bar 46 is located lengthwise of the cylinder at said opposite end of the opening, the other end of the tympan being gripped between said bar and the adjacent edge of the cylinder wall at said opening 37. Radial arms 47 integrally connected with the bar 46 extend to the sleeve 39 and are provided with bearings 48 at their inner ends which surround the sleeve. Thumb screws 49 passing through the arms 47 thread into an inward projection 35a on the cylinder for pressing bar 46 against the end of the tympan and pressing the tympan against the adjacent edge of the cylinder at the opening 37 thereof.

A second bar 50, paralleling the bar 46 and located adjacent the elongated sleeve 39, is integral with the arms 47. In a plurality of aligned

radially disposed openings through the parallel bars 46 and 50, pins 51 are passed, each at its outer end having a flat head 52, the diameter of which is equal to or slightly greater than the width of the bar 46. Each of the pins has a coiled compression spring 53 around it, one end bearing against the inner side of bar 46 and the other against a washer 54 located between the bars 46 and 50, one around each of the pins 51 which are held in position thereon by suitable means as by cotter pins. Such springs under compression tend to force the pins inwardly and bring the inner sides of the heads 52 of the pins 51 against the outer side of bar 46, or against an edge of a proof sheet of paper inserted between them.

The sleeve 39 at the inner end of each of the pins 51 is recessed for substantially half of its circumference and in each recess a cam 56 is located and permanently secured to the rod 40. Thus when the rod is turned and before pin 43 engages with the sleeve 39 to turn it and the cylinder connected therewith, the cam members 56 move with the rod. In one direction of turning rod 39 the inner ends of the pins 51, riding upon the cam surfaces, force said pins outwardly to the position shown in Fig. 6. But on reverse turning movement of the rod 41, the cam members 56, moving clockwise with the rod, will move away from the inner ends of the pins 51, which pins follow the retreating cam surfaces under pressure of the springs 53, and move the heads 52 inwardly to clamping or gripping position.

The proof sheet which is to be printed is laid upon the inclined table 57 at the upper outer portion of the carriage and its inner edge brought between the bar 46 and the gripping heads 52, with said heads in outer position as in Fig. 6. The cylinder remains stationary and does not move during the first movement of the crank 41. Such first movement of the crank 41, turning the rod 40 until the ends of pins 43 have traversed the slots 42, at the same time releases the pins 51 so that the gripping heads 52 engage against and grip the end edge of the paper against bar 46 before the cylinder starts to turn. With the carriage and tracks in lower position, the rotation of the cylinder and the accompanying turning of the gears 38 causes the carriage to move along the tracks with a simultaneous turning of the cylinder and a succeeding pressing of the paper proof sheet against the outer side of the printing form 7 which remains stationary on the bed 5. The gripping heads 52, in the rotation of the cylinder in a clockwise direction (Fig. 6), miss the end of the form 7 which contacts the paper a short distance back of the gripping heads.

Foot operation of the lever 29 moves the cams 20 so that the springs 17 may lift the cylinder above the form 7 at any time that it may be wanted. There is no disengagement or partial disengagement of the gears 38 and the racks 30 at any time during operation of the press. The inking and inking roller equipment 58 is likewise lifted above the upper surface of the type form. On the return of the carriage to its initial position, the first movement in initiation of such return is to turn the rod 40 in a reverse direction, thereby releasing the gripping heads 52 before the carriage starts to move back or the cylinder starts its rotation in the opposite direction. When the carriage has been moved back and is stopped at its initial position, the cylinder occupies the identical position which it had at the beginning of the proof sheet printing operation, and is ready

to grip the end edge of a succeeding paper sheet to be printed and perform the same cycle of operations with respect thereto.

With the structure described, the gripping and the release of the paper is done while the cylinder is stationary. This is a very desirable result of my invention. Such release of the gripping of the paper is accomplished at any position of the carriage by merely reversing the turning of the crank handle 41. The cylinder does not change position in the slightest from any impression position in which it may be located in the operation of the mechanism, as the gears 38 and the racks 30 are always in full mesh. The elevation of the cylinder after a proof sheet has been printed is done before the return of the carriage to initial position. The printed proof sheet is released from the gripping heads 52, so that on return of the carriage and cylinder to the initial position, the printed sheet is left over the form and beyond the carriage and may be readily removed.

The proof press described has been produced and is in use and is exceptionally satisfactory in operation.

The invention is defined in the appended claims and is to be considered comprehensive of all forms of structure coming within their scope.

I claim:

1. In a structure as described, an elongated horizontal type bed, longitudinal track bars one at each side thereof, a carriage including two spaced apart sides, one adjacent each of said track bars, means for mounting the carriage on the bars for movement of the carriage back and forth thereon, a horizontal cylinder extending between the sides of the carriage, bearing connections between said cylinder and track bars for moving the carriage and the cylinder therewith in one direction on said track bars when said cylinder is turned in one direction and in the opposite direction when the cylinder is reversed in turning movement, said cylinder being hollow and at one side having an opening extending the length thereof, an elongated sleeve extending axially of the cylinder to which the cylinder is connected, said sleeve being rotatably mounted on the carriage sides, a rod extending through the sleeve, a crank secured to one end of the rod, said sleeve at an end thereof having diametrically opposed recesses therein, a pin extending through the rod the end portions thereof being received in said recesses, said recesses in length being greater than the diameter of said pin, sheet gripper means mounted on said cylinder, means for moving said gripper means outwardly on turning the rod in one direction and for releasing said gripper means inwardly on turning said rod in the opposite direction, and spring means moving said gripper means inwardly when released.

2. In a proof press, a carriage adapted to be mounted for moving back and forth over a type bed, said carriage having spaced apart sides, a hollow cylinder having a segment longitudinally thereof open, an elongated sleeve extending through the cylinder and on which the cylinder is fixed, said sleeve at its ends being rotatably mounted on said sides of the carriage, a bar secured to the cylinder at one side of the open segment thereof, said bar extending lengthwise of said cylinder, a second bar connected therewith located parallel thereto and to said sleeve, a rod extending through the sleeve, a crank handle secured to one end of the rod, pins passing through said bars having gripping heads at their outer

ends, said pins at their inner ends being directed toward said sleeve and rod, spring means one on each pin, tending to move the pins radially inward, said sleeve at the inner end of each pin having a recessed portion therein extending to said rod, a cam connected to said rod and located in each recess, the inner ends of said pins bearing against said cams, and inter-engaging means between the rod and sleeve for connecting the rod with the sleeve to turn said sleeve upon turning the rod a limited amount, said rod when turned in either direction first turning said limited amount before connecting with said sleeve to turn it and its attached cylinder, whereby on turning the rod in one direction said pins are released for automatic inward movement to bring the gripping heads thereof against the face of the outer bar before rotation of the cylinder begins, and on reversal of movement of the rod, said pins are forced outwardly away from operative gripping 20

position before reverse turning movement of the cylinder begins.

3. A structure as defined in claim 2, said inter-engaging means between the rod and cylinder comprising, a pin extending transversely through the rod and having end portions extending beyond the sides of the rod, said sleeve having recesses into which said end portions of the pins extend, the length of said recesses being greater than the diameter of the pin.
